UNITED STATES PATENT OFFICE.

THOMAS W. SOUTHARD, OF WILLIAMSPORT, PENNSYLVANIA.

RULE ATTACHMENT.

1,110,968.

Specification of Letters Patent.

Patented Sept. 15, 1914.

Application filed March 3, 1913. Serial No. 751,906.

To all whom it may concern:

Be it known that I, THOMAS W. SOUTHARD, a citizen of the United States, residing at Williamsport, in the county of Lycoming and State of Pennsylvania, have invented new and useful Improvements in Rule Attachments, of which the following is a specification.

This invention has reference to attachments for rules, and it proposes, briefly, an improved appliance, in the nature of a gage, which may be readily attached to and removed from the ordinary two-foot carpenter's rule, whereby the latter may be employed for accurately laying out gage lines and miters, and may be used as a depth gage, try- or T-square.

It further comprehends an appliance of the type specified which is automatically held in adjusted position on the rule, is correct and reliable in its adjustment, since it contains no joints to wear or become loose, and in general, is extremely simple, durable and inexpensive.

An embodiment of the invention is illustrated in the accompanying drawing, whereof:—

Figure 1 is a perspective view of the improved gage applied to a rule; Fig. 2 is an enlarged inverted transverse section, taken on the line 2—2, Fig. 1; Figs. 3 and 4 are perspective views of the gage, taken from opposite sides.

As shown in said drawing, the gage is constructed from a single blank of sheet metal, for instance, spring-tempered brass, steel or aluminum, so as to insure the desired resilient gripping action of the hereinafter-described rule-engaging flanges.

This blank, during the stamping operation by which it is produced, is so acted upon by the dies as to form the flange 6 at one end thereof, and the flanges 7 and 8 at the other end. The flanges 7 and 8 are disposed at a

right angle to each other, the imaginary line bisecting such angle also bisecting the opposite flange 6 and being perpendicular thereto. The apex of this angle is directed away from flange 6, so that the latter thus con-

stitutes a portion of the base of an imaginary isosceles triangle whose equal sides form a right-angle and are constituted, in part, by the flanges 7 and 8. During the stamping or similar operation, the blank is also formed with a pair of parallel slits 9

and 10 which intersect the junction, or fold line, between the body 5 of the blank and the base flange 6. The tongues 11 and 12 produced by these slits are bent outward or away from the blank body 5, and in the opposite direction from the flanges 6, 7 and 8. Also, they have a slight inward inclination toward each other. The slits 9 and 10 are so positioned that when the tongues are bent in the manner above indicated, they will be disposed a distance apart which is approximately equal to the combined width of the two sections 13 of a standard rule, the width of the slits being such that the said tongues will have a height approximately equal to the thickness of a section. The tongues, therefore, may be considered as constituting the afore-mentioned rule-engaging flanges.

By reason of this construction and arrangement, the finished gage may be readily applied to either half of the rule, in the manner represented in Fig. 1, and then slid along the same in either direction, the inherent resiliency and inward inclination of its tongues or flanges 11 and 12 causing them to grip the rule sufficiently tightly to hold the gage in any position into which it may have been moved. Also, the gage may be applied against either side of the rule, and with the apex of the angle formed by the flanges 7 and 8 pointing in either direction, but it will be understood that in removing the gage from the rule it must be slipped off the end of the latter, and, equally, must be fitted upon the end of the rule when it is to be used thereon, this being due to the frictional grip of the side flanges 11 and 12 upon the rule. For the same reason, the gage will not drop from the rule after having been adjusted, nor does it require the use of extraneous clamping devices for retaining it in adjusted position.

The mode of operation is, briefly, as follows: When used for obtaining gage lines, the base flange 6 is held against one edge of the work with the rule extending across the face thereof and the said flange projecting downward. The rule may then be moved along the work and a pencil or other marker held against the edge of the rule at the proper point. In like manner, the afore-said flange 6 may serve as the head of a T-square and the rule as the blade thereof, the rule extending across the upper face of a

drawing board and the flange 6 engaging one of its edge faces. Also, the implement, as a whole, may be used as a try-square, to square the ends of floor and siding planks and boards, thus permitting the same to be cut so as to make perfect joints.

The flanges 7 and 8, by reason of their right-angular disposition, enable miters to be readily marked and cut, one of such flanges being used for the right-hand half of the miter, and the other flange for the left-hand half. Furthermore, the implement may be employed as a depth gage by holding the end of the rule against the bottom of the mortise or other groove, and then sliding the gage upwardly until the flange 6 is flush with the upper surface of the work, and it may be used for gaging lines concentric with a curved edge by holding the apex 15 of the angular flange against the said curved edge and moving it therealong.

It is finally to be observed that the entire gage is constructed in one piece, for which reason, its cost of manufacture is reduced 20 to a minimum, while, at the same time, its durability and efficiency are correspondingly increased, since it has no joints to wear and impair its accuracy.

The rule engaging flanges 11 and 12, as previously stated, and as best shown in Fig. 2, are so bent at their junction with the body 5 of the blank as to form a slight

curve, rather than a true right angle, although it will be understood that when the gage is applied to a rule, the outer portions 35 of these flanges grip the edges of the latter, and, in consequence, may be considered as disposed approximately at right angles to the body of the gage. By providing this gradual bend, instead of an abrupt bend, 40 such as would be the case if the flanges were bent directly at right angles to the body of the gage, the gage is not weakened at the point where the flanges join it.

Having described my invention, I claim: 45

An attachment for pocket-rules consisting of a resilient, sheet metal blank having a base flange at one end, and a right-angular flange at the other end, and formed with a pair of parallel slits, the portions of said blank defined by said slits being bent outwardly from the body of the blank in the opposite direction from said flanges but being inclined toward each other, to produce a pair of spring clamping flanges for engagement with the opposite side edges of the rule.

In testimony whereof I have hereunto set my hand in presence of two subscribing witnesses.

THOMAS W. SOUTHARD.
